UNITED STATES PATENT OFFICE.

THURE A. JOHANSON AND FRANCIS C. SOCIN, OF ST. CHARLES, ILLINOIS, ASSIGNEES
TO THE CABLE COMPANY, OF CHICAGO, ILLINOIS, A CORPORATION OF ILLINOIS.

FALL-BOARD AND MUSIC-DESK CONSTRUCTION.

Application filed January 6, 1923. Serial No. 610,990.

To all whom it may concern:

Be it known that we, THURE A. JOHANSON and FRANCIS C. SOCIN, citizens of the United States, residing at St. Charles, in the 5 county of Kane and State of Illinois, have invented new and useful Improvements in Fall-Board and Music-Desk Construction, of which the following is a full, clear, concise, and exact description, reference being had 10 to the accompanying drawings, forming a part of this specification.

This invention relates to piano construction, and more particularly to the construction of the piano fall-board and music-desk- 15 support.

One of the objects of the invention is to provide an improved construction in which the fall-board is supported in a manner pro- 20 viding for its easy removal and replacement.

Another object of the invention is to pro- 25 vide improved means for guiding the movement of the fall-board, which means is de- signed to permit the free removal and easy replacement of the fall-board in proper as- sociation therewith.

Another object of the invention is to pro- 30 vide an improved construction and arrange- ment of the fall-board and of the music-desk- support, through which an inward move- 35 ment of the fall-board will move the music- desk into its inclined position and lock it in such position.

A further object of the invention is to pro- 40 vide an improved construction of the fall- board and of the music-desk-support which will be durable and efficient in use.

Further objects will appear from the de- 45 tailed description to follow and from the appended claims.

In the drawings, in which an embodiment 50 of the invention is shown--

Figure 1 is an elevational view of the 55 front of a piano, parts being broken away;

Fig. 2 is a vertical fore-and-aft section 60 through the forward upper part of the instrument, with the fall-board in its inward or "pushed back" position and the music- desk in its forwardly swung or "pushed out" position;

Fig. 3 is a view on the same plane as Fig. 2, but showing the fall-board in its forward, key-covering position and the music-desk in its inward, vertical position;

Fig. 4 is a section on the line 4—4 of Fig. 1; and

Fig. 5 is a section on the line 5—5 of Fig. 4.

Referring now to the drawings in detail, the construction shown therein comprises a fall-board 10 and a music-desk 11, as well as 60 certain other usual parts of an upright piano, such as the keys 12 and parts of the casing.

The fall-board 10 comprises forward and rearward sections 13 and 14, respectively, 65 hinged together at 15 and extending horizontally over the keys 12 between the side-arms 16, as shown in Fig. 3. The rearward section 14 rests and is horizontally slidable upon guides 17, which are secured upon the 70 side-arms 16, and the forward section 13 may be turned upon the hinge 15 from closed po- 75 sition (Fig. 3) to open position (Fig. 2) so that it lies on top of the rearward section. It will be observed that, in the closed po- 80 sition of the fall-board shown in Fig. 3, in which it is drawn forward as far as the stops 12^a will allow, the hinge is so positioned over the keys 12 that the simple turning of the section 13 to rest upon the section 14 would 85 not render the keys properly accessible for playing. Provision is therefore made for the pushing back of the folded sections to a position (shown in Fig. 2) which entirely exposes the key-board, such rearward move- 90 ment of the sections being limited by a pair of stop-pins, one of which is shown at 18, se- 95 cured to the piano casing and located in a position to be engaged by a corresponding pair of cushion-members 19 secured to pro- 100 ject from the rearward face of the vertical board 20, near the opposite ends thereof. The vertical board 20 is secured to, and is movable with, the section 14, serving as a stiffening flange for said section and consti- 105 tuting a part of the casing, closing the space between the music-desk 11 and the section 14 when the fall-board is in closed position.

In order to insure the proper parallel movement of the fall-board during the 100 sliding of section 14 upon the guides 17, a rock-shaft 21, having two upstanding par- 105 allel arms 22 and 23, is rotatably secured upon a fixed part of the instrument and the upper end parts of the two arms are ar- ranged to cooperate with the opposite sides

or end parts of the section 14. As shown herein, the rock-shaft may be formed of a single, round, horizontally arranged rod having its end parts bent upwardly to form 5 the two arms 22 and 23, the shaft proper being positioned within a groove or recess 24 in the key-bed 25, and retained therein by the cap-blocks 26. The rock-shaft is thus positioned below the upper surface of the 10 key-bed and extends beneath and transversely of the usual removable frame (not shown) which carries the keys 12, the arms 22 and 23 being preferably arranged to project upwardly at points outside of this key-frame, so that no part of the device will interfere with the removal and replacement of the key-frame. While this construction and arrangement of the rock-shaft is simple, economical, and efficient, it is obvious that it 15 may be otherwise constructed and arranged without necessarily modifying its efficiency. It may be arranged upon, within, or beneath the key-bed, or suitably secured to the side-arms 16, the length of the arms 22 and 23, 20 the details of their construction, and the method of their firm connection with the rock-shaft being of minor importance. Socket-members 27 and 28 are secured upon the under side of the section 14, near its opposite rearward corners, to removably but 25 securely engage with the upper end parts of the arms 22 and 23, respectively, and it is therefore obvious that a twisting or racking of the fall-board cannot occur during its 30 sliding movement without twisting the rock-shaft 21, which should, of course, be strong enough to prevent such occurrence.

In order to secure the fall-board against 35 disarrangement during transportation of the instrument, it has been deemed advisable to arrange a latch 29 (Figs. 4 and 5) which may be adjusted to prevent or permit the removal of the section 14 from the guides 17. The provision of one such latch has been 40 found sufficient, and it is shown pivoted to the rearward end part of socket-member 28, but a second latch may be similarly arranged, if desired, in connection with the other socket-member 27. The latch 29 consists of a simple lever 30, pivoted between 45 its ends at 31 to the socket-member 28, the shorter arm or point of the lever extending beneath the adjacent guide 17 and the longer arm thereof projecting sufficiently for convenient manipulation.

As is usual in modern upright piano construction, the music-desk 11 is formed by swinging or tilting the upper panel of the casing at an angle which will provide a 50 properly arranged backing against which music-sheets or music-books may be rested. The panel is therefore pivoted to a fixed part of the casing, as at 32, and provision is made for causing it to be automatically swung or 55 tilted to a proper degree through the move-

ment of the fall-board to expose the keys for playing. Devices of the type shown herein for effecting this automatic adjustment of the music-desk are technically known as "kickers", but their employment, while quite extensive, has been almost exclusively in connection with fall-boards radically different in design and operation from that shown herein. In many such uses of this simple form of music-desk-support, the weight of 70 the fall-board or the method of hinging it contributed the only means for holding the support to keep the music-desk firmly positioned against the weight or leaning pressure of music-books of any considerable size. 75

As shown in Fig. 1, a pair of kicker-levers 33 and 34 are provided for supporting the music-desk at its opposite sides, each lever being pivoted between its ends upon a relatively fixed part of the instrument,—in this 80 instance the respective side of the piano casing. Both levers are alike and a description of one will therefore suffice. The lever 33 is formed of a round rod, flattened at a point intermediate its ends and pivoted at 85 such point upon a screw 35, which transfixes the lever and holds it in position so that the upper arm 36 thereof will engage the inner face of the music-desk 11 and the lower arm 37 thereof will be engaged by the rearward 90 end of the socket-member 27. The lower arm of the lever is bent, as shown at 38 and 39, to provide a locking shoulder 40 which co-operates with an abutment 41 secured to the rearward face of the vertical board 20. 95

With this construction, when the fall-board 10 is in the fully open, pushed back position shown in Fig. 2, the shoulder 40 will be in engagement with the abutment 41, the abutment resting beneath and in engagement with the then substantially horizontally positioned portion of the lever 33 between the bends 38 and 39, preventing the downward swinging of such portion and thus firmly locking the lower arm 37 100 against forward movement. The upper arm 36 of the lever is thus firmly held in its forwardly swung position, supporting the music-desk in its forwardly swung position. When the fall-board is in the closed position 105 shown in Fig. 3, the section 14 thereof will be in its forward position upon the guides 17, the abutment 41 will likewise be forward of and free from engagement with the shoulder 40, and the upper panel which forms the 110 music-desk 11 will be permitted to occupy its normally vertical position, the kicker-lever 33 being free to swing so that the lower arm 37 thereof will rest against the rearward end of the socket-member 27. 115

The operation of the parts described are as follows:

When it is desired to remove the fall-board from the instrument, the longer arm 120 of the latch-lever 30 should be moved rear- 125 ward. 130

wardly to free the point of the lever from engagement with the under side of the respective guide 17, and the fall-board will be free to be lifted bodily from the guides.

5 It will be observed that the arms 22 and 23 are not attached to their respective co-operating socket-members 27 and 28. The lifting of the section 14 from the guides 17 simply lifts the attached socket-members off 10 from the ends of the arms and, in replacing the fall-board, it is only necessary to see that the socket-members are slipped over the ends of the upstanding arms and that the latch-lever is moved forwardly into locking 15 position, as shown in Fig. 4. In order to facilitate this slipping of the socket-members over the ends of the upstanding arms, stop-blocks 42 are provided for the arms to support them conveniently in forwardly 20 swung position.

In opening the fall-board, the forward section 13 is turned upon the hinge 15, over and back upon the top of the rearward section 14, and the sections thus folded are then 25 pushed rearwardly into the position shown in Fig. 2, at which point the rearward movement is stopped by the abutment of the cushion-members 19 against their respective stop-pins 18. In this rearward movement 30 of the fall-board, the rearward section 14 thereof slides along upon the guides 17, and the socket-members 27 and 28 rock their respective rock-shaft-arms 22 and 23 and push the lower arms 37 of their respective kicker- 35 levers 33 and 34 rearwardly. Since the two arms 22 and 23 are fixed upon the rock-shaft 21, they must rock together and the two socket-members 27 and 28, with which they respectively co-operate, must likewise move 40 together. This simultaneous movement of the socket-members results in a parallel movement of the fall-board, to which they are secured, and a correspondingly simultaneous swinging of the two kicker-levers 45 33 and 34, against the lower end parts of which they impinge. As the two kicker-levers are thus simultaneously swung about their pivotal points 35, the upper end parts 50 of the upper arms 36 thereof push forward upon the rearward face of the music-desk 11 and it is swung forwardly upon its pivots 32 into its music-supporting position, at which point all of the parts will occupy 55 their several positions as shown in Fig. 2. 60 As the lower arms 37 of the two kicker-levers 33 and 34 are pushed rearwardly by the respective socket-members 27 and 28, the shoulders 40 are swung rearwardly and upwardly about the pivotal points 35 until, at 65 the end of such swinging, the portions of the levers 33 and 34 between the bends 38 and 39 have assumed a substantially horizontal position. During this rearward and upward swinging of the shoulders 40, the rearward movement of the fall-board 10 pushes

the abutments 41 beneath the shoulders, the shape of the shoulders being so designed that, as the portions between the bends 38 and 39 are swung toward their substantially horizontal positions, the abutments 41 are 70 simultaneously entered therebeneath in substantially constant contact with said portions. At the end of this rearward movement of the fall-board, the shoulders 40 will be supported upon the abutments 41, and 75 the lower arms 37 of the two kicker-levers will have been moved out of contact with the socket-members 27 and 28, and the music-desk 11 will consequently be locked in its 80 forwardly swung, music-supporting position. Forward movement of the fall-board, from the open position shown in Fig. 2, withdraws the abutments 41, and the operation of the several parts will obviously be 85 the reverse from that just described.

Having thus described our invention, what we claim as new and desire to secure by Letters Patent of the United States is:

1. The combination, with the key-frame, key-bed, and fall-board of a piano, of means 90 for mounting said fall-board for inward and outward parallel motion above said key-frame, comprising a rock-shaft arranged to extend transversely beneath said key-frame below the upper surface of said key-bed and having a pair of upwardly extending arms, one at each end of said rock-shaft beyond the side limits of said key-frame and connected with said fall-board, whereby said rock-shaft and the said upwardly extending 95 arms thereof do not interfere with the removal of said key-frame.

2. The combination, with the key-frame, key-bed, and fall-board of a piano, of means 100 for mounting said fall-board for inward and outward parallel motion above said key-frame, comprising a rock-shaft arranged to extend transversely beneath said key-frame below the upper surface of said key-bed and having a pair of upwardly extending arms, 105 one at each end of said rock-shaft beyond the side limits of said key-frame and connected with said fall-board, said fall-board being provided with sockets freely receiving the upper ends of said arms, whereby the 110 fall-board may be readily lifted away from said arms and said key-frame may be removed free from interference therewith by said rock-shaft and the upwardly extending 115 arms thereof.

3. A piano fall-board and music-desk construction comprising a fall-board mounted for inward and outward movement, a music-desk mounted for inward and outward movement, and means whereby inward movement of said fall-board will cause outward movement of said music-desk and will lock said music-desk in its outer position; said means comprising a pivotally mounted 125 rock-arm acting on said music-desk and hav- 130

ing a shoulder thereon, and said fall-board being provided with an abutment movable underneath and engaging said shoulder to hold said rock-arm in position to hold said 5 music-desk in its outer position.

4. A piano fall-board and music-desk construction comprising a fall-board mounted for inward and outward movement, a music-desk mounted for inward and outward movement, 10 and means whereby inward movement of said fall-board will cause outward movement of said music-desk and will lock said music-desk in its outer position; said means comprising a pivotally mounted rock-arm 15 acting on said music-desk and having a bend therein underneath which said fall-board moves and with which it engages to hold said rock-arm in position to hold said music-desk in its outer position.

20 5. A piano fall-board and music-desk construction comprising a fall-board mounted for inward and outward movement, a music-desk mounted for inward and outward movement, and means whereby inward 25 movement of said fall-board will cause outward movement of said music-desk and will lock said music-desk in its outer position; said means comprising a member controlled by the movement of said fall-board and having 30 a shoulder thereon, and said fall-board being provided with an abutment movable underneath and engaging said shoulder to hold said member in position to hold said music-desk in its outer position.

35 6. A piano fall-board and music-desk construction comprising a fall-board mounted for inward and outward movement, a music-desk mounted for inward and outward movement, and means whereby inward movement 40 of said fall-board will cause outward movement of said music-desk and will lock said music-desk in its outer position; said means comprising a member actuated by the movement of said fall-board and having a bend 45 therein underneath which said fall-board moves and with which it engages to hold said member in position to hold said music-desk in its outer position.

7. The combination, with the keys, key-bed, and fall-board of a piano, of means for 50 mounting said fall-board for inward and outward parallel motion above said keys, comprising a rock-shaft arranged to extend transversely beneath said keys below the upper 55 surface of said key-bed and having a pair of upwardly extending arms, one at each end of said rock-shaft beyond the range of said keys and connected with said fall-board, whereby said rock-shaft and the said 60 upwardly extending arms thereof do not interfere with the bodily removal of the entire range of said keys.

8. The combination, with the keys, key-bed, and fall-board of a piano, of means for 65 mounting said fall-board for inward and

outward parallel motion above said keys, comprising a rock-shaft arranged to extend transversely beneath said keys below the upper surface of said key-bed and having a pair of upwardly extending arms, one at 70 each end of said rock-shaft beyond the range of said keys and connected with said fall-board, said fall-board being provided with sockets freely receiving the upper ends of said arms; whereby the fall-board may be 75 readily lifted away from said arms and the entire range of said keys may be bodily removed free from interference therewith by said rock-shaft and the upwardly extending arms thereof. 80

9. A piano fall-board and music-desk construction comprising a fall-board mounted for inward and outward movement, a music-desk mounted for inward and outward movement, and means whereby inward movement 85 of said fall-board will cause outward movement of said music-desk and will lock said music-desk in its outer position; said means comprising a rock-arm pivotally supported between its ends to swing vertically, the 90 upper end-part thereof acting directly upon said music-desk and the lower end-part thereof engaging with said fall-board, such lower end-part of said rock-arm being provided with a shoulder, and said fall-board 95 being provided with an abutment movable underneath and cooperating with said shoulder to hold said rock-arm in position to hold said music-desk in its outer position.

10. A piano fall-board and music-desk 100 construction comprising a fall-board mounted for inward and outward movement, a music-desk mounted for inward and outward movement, and means whereby inward movement of said fall-board will cause 105 outward movement of said music-desk and will lock said music-desk in its outer position; said means comprising a rock-arm pivotally supported between its ends to swing vertically, the upper end-part thereof acting directly upon said music-desk and the lower end-part thereof engaging with said fall-board, such lower end-part of said rock-arm 110 having a bend therein underneath which said fall-board moves and with which it 115 cooperates to hold said rock-arm in position to hold said music-desk in its outer position.

11. A piano fall-board and music-desk construction comprising a fall-board mounted for inward and outward movement, a 120 music-desk mounted for inward and outward movement, and means whereby inward movement of said fall-board will cause outward movement of said music-desk and will lock said music-desk in 125 its outer position; said means comprising a pair of pivotally mounted rock-arms acting individually on said music-desk at the right and left side-parts thereof, each of said rock-arms having a shoulder 130

thereon, and means for guiding said fall-board whereby inward movement of said fall-board will cause the respective end-parts thereof to be simultaneously moved into engagement with said shoulders to hold each of said rock-arms in position to hold said music-desk firmly in its outer position.

12. A piano fall-board and music-desk construction comprising a fall-board mounted for inward and outward movement, a music-desk mounted for inward and outward movement, and means whereby inward movement of said fall-board will cause outward movement of said music-desk and will lock said music-desk in its outer position; said means comprising a pair of pivotally mounted rock-arms acting individually on said music-desk at the right and left side-parts thereof, each of said rock-arms having a bend therein, and said fall-board being provided with an abutment movable into engagement with the bend in each of said rock-arms and with means for guiding said fall-board, whereby inward movement of said fall-board will cause said abutments to simultaneously move into engagement with the bends in the respective rock-arms and co-operate therewith to hold said rock-arms in position to hold said music-desk firmly in its outer position.

13. The combination, with the key-bed and frame of a piano, of a fall-board; means for mounting said fall-board for inward and outward parallel movement, comprising a rock-shaft below the upper surface of said key-bed having a pair of upwardly extending arms, one at each end thereof, connected with said fall-board; a music-desk mounted for inward and outward movement; and means whereby inward movement of said fall-board will cause outward movement of said music-desk and will lock said music-desk in its outer position, the last said means

comprising a pair of rock-arms pivotally mounted upon opposite sides of said frame to act individually on said music-desk at the right and left side-parts thereof, each of said rock-arms having a shoulder thereon; whereby, upon inward movement of said fall-board, the respective end-parts thereof will be simultaneously moved into engagement with said shoulders to hold each of said rock-arms in position to hold said music-desk firmly in its outer position.

14. The combination, with the key-bed and frame of a piano, of a fall-board; means for mounting said fall-board for inward and outward parallel movement, comprising a rock-shaft below the upper surface of said key-bed having a pair of upwardly extending arms, one at each end thereof, connected with said fall-board; a music-desk mounted for inward and outward movement; and means whereby inward movement of said fall-board will cause outward movement of said music-desk and will lock said music-desk in its outer position, the last said means comprising a pair of rock-arms pivotally mounted upon opposite sides of said frame to act individually on said music-desk at the right and left side-parts thereof, each of said rock-arms having a bend therein, and said fall-board being provided with an abutment movable into engagement with the bend in each of said rock-arms; whereby inward movement of said fall-board will cause said abutments to simultaneously move into engagement with the bends in the respective rock-arms and co-operate therewith to hold said rock-arms in position to hold said music-desk firmly in its outer position.

In witness whereof, we have hereunto subscribed our names.

THURE A. JOHANSON.
FRANCIS C. SOCIN.
